UNITED STATES PATENT OFFICE.

THEODOR AHLBORN, OF CHICAGO, ILLINOIS.

DESIGN FOR A PORTABLE COTTAGE.

Application filed June 28, 1926. Serial No. 18,199. Term of patent 3½ years.

To all whom it may concern:

Be it known that I, THEODOR AHLBORN, a citizen of the United States, residing at Chicago, in the county of Cook and State of Illinois, have invented a new, original, and ornamental Design for Portable Cottages, of which the following is a specification, reference being had to the accompanying drawing, forming part thereof.

I claim:

The ornamental design for a portable cottage, as shown.

In testimony whereof I affix my signature at 10 South La Salle Street, Chicago, Illinois.

THEODOR AHLBORN.
